Heinrich Jost

by *Paul D. Schellie*
his attorney.

UNITED STATES PATENT OFFICE.

HEINRICH JOST, OF KREUZLINGEN, SWITZERLAND, ASSIGNOR TO EMIL RUTISHAUSER,
OF KREUZLINGEN, SWITZERLAND.

TEMPLET.

1,379,630.

Specification of Letters Patent. Patented May 31, 1921.

Application filed December 31, 1918. Serial No. 269,066.

To all whom it may concern:

Be it known that I, HEINRICH Jost, a citizen of the Swiss Confederation, and residing at Kreuzlingen, Switzerland, have invented certain new and useful Improvements in Templets, of which the following is a specification.

The present invention has reference to certain new and useful improvements in templets such as are used for cutting out and marking leather and like soft material, for instance shoe uppers and the like.

For cutting out and marking certain work pieces, for instance vamps and other shoe parts, so that they can readily be placed upon one another in the correct position for being glued or stitched together, templets are now used which are provided with apertures through which the underlying work piece is marked by the insertion of a suitable pointed tool, but their use has several disadvantages: for instance that often through carelessness on the part of the operator not all of the required locations are marked, that the leather is unnecessarily perforated, bruised or otherwise injured, and also that the templet itself is apt to be damaged by the marking tool.

According to the present invention these disadvantages are effectively done away with by providing the templet body at the points to be marked off with excrescences of such conformation that upon being impressed on the leather they will leave a permanent mark therein without at the same time bruising or otherwise injuring it. A special marking tool, therefore, can be dispensed with. The impressed marks are then used as guides in adjusting another work piece on this marked piece in proper register.

In order to make my invention more readily understood, I will now describe it in detail with reference to the accompanying drawing, in which Figure 1 represents a plan of a portion of such a templet, showing the simplest form of marking members; Fig. 1^a is a plan of a portion of a templet showing marking members of somewhat modified construction. Fig. 2 is a section on

line A—A of Fig. 1; and Fig. 3 a similar section on line B—B of Fig. 1^a; Fig. 4 is a plan of a marking member fastening device, of which Figs. 5 and 6 show sections of different designs.

55

The body of the templet 1, which may be incased by a metal rim 2, is provided at the points to be marked off on the underlying work material with relatively short and somewhat blunted studs or knobs 3, which may be secured to the templet in any suitable manner, for instance by simply driving in their sharp pointed inner end 4, or by screwing them in, as at 5 (Fig. 2). They can readily be displaced on the templet to suit changing requirements. Instead of being secured direct to the templet, these knobs may also be suitably mounted upon (Fig. 5), or integrally extend (Fig. 6) from special base plates 6, shown in plan in Fig. 4, of for instance triangular shape, whose apexes are rectangularly bent off to form a spike or prong 7 by means of which the plates are then attached to the templet by being hammered into it.

75

In use, the templet is superimposed upon the leather and is more or less forcibly pressed down upon it, whereupon the edge tool is guided along the metal rim for cutting out the ground pattern. By the pressure exerted on the templet the marking studs 3 will be sunk into the leather and will leave their mark therein after the templet has been lifted off, without damaging the leather and without possibility of one of the points to be marked off having been left unmarked.

80

What I claim is:—

In a templet of the character set forth, in combination, a templet body proper, marking members adapted to be relatively displaceably secured to said templet body, each comprising a triangular base plate, prongs rectangularly extending from said base plate and obtained by bending-over the pointed apexes of said triangular plate, and a marking stud extending centrally from said base plate in a direction opposed to that of said prongs.
